(57) **CLAIM**

The ornamental design for a headwear, as shown and described.

DESCRIPTION

FIG. 1 is a rear, side perspective view of the headwear in accordance with the present design;
FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and,

FIG. 8 is a front, perspective view of the headwear of FIGS. 1-7, illustrating electrodes installed in the receptacles of the headwear shown in FIGS. 1-7.

The broken lines showing the electrodes in FIG. 8 represent environmental structures and form no part of the claimed design.

1 Claim, 7 Drawing Sheets
